DESIGN FOR A FLOWERPOT

Harry Ratner, Great Neck, N. Y.

Application June 14, 1940, Serial No. 93,008

Term of patent 14 years

To all whom it may concern:

Be it known that Harry Ratner, a citizen of the United States and resident of Great Neck, in the county of Nassau and State of New York, has invented a new, original, and ornamental Design for a Flowerpot, of which the following is a specification, reference being had to the accompanying drawing, forming part thereof, in which,

Fig. 1 is an elevational view of a flowerpot embodying my new design;

Fig. 2 is a cross-sectional view thereof taken substantially on the line 2—2 of Fig. 1 partly cut away for convenience of illustration.

I claim:

The ornamental design for a flowerpot, substantially as shown.

HARRY RATNER.
